UNITED STATES PATENT OFFICE.

FREDERICK W. BÖSCH, OF CAMDEN, NEW JERSEY, ASSIGNEE TO WORTHINGTON PUMP
AND MACHINERY CORPORATION, OF NEW YORK, N. Y., A CORPORATION OF VIR-
GINIA.

STEAM-ENGINE.

1,401,867.

Specification of Letters Patent. Patented Dec. 27, 1921.

Application filed August 23, 1916, Serial No. 116,440. Renewed April 29, 1919. Serial No. 298,578.

To all whom it may concern:

Be it known that I, FREDERICK W. Bösch, a citizen of the United States, residing at Camden, in the county of Camden and State 5 of New Jersey, have invented certain new and useful Improvements in Steam-Engines, of which the following is a specification.

My invention relates to improvements in steam engines of the construction generally 10 designated as the uniflow type, and in which the live steam enters the cylinder at the ends thereof and the expanded steam is first exhausted through ports at or near the end of the stroke, distant from the admission ports, 15 said ports being uncovered by the piston within the cylinder at or near the end of its working stroke and said exhausted steam finally conveyed by exhaust diverting valve or valves either directly to the atmosphere 20 or condenser, or to a heating system or other lower pressure steam using expedients and condenser.

The objects of my invention are:

First, to construct an engine of the uniflow type capable of effecting all the functions above recited and also in which all the advantages of said type of engine are 25 fully carried out without necessitating the use of abnormally long cylinder and piston 30 and long ports or connecting passageways to the final exhaust.

Second, to construct an engine of the uniflow type, performing all the functions above indicated, in which the clearance and back 35 pressure are reduced to a minimum and at the same time prevent the compression from exceeding the initial live steam pressure, thereby insuring the highest efficiency and economy at all speeds of the engine under 40 all conditions.

Third, to construct an engine of the uniflow type in which the cylinder is provided with such an arrangement of admission and combined main and auxiliary exhaust ports 45 controlled by the piston and by suitable valve mechanism, and final exhaust diverting valve mechanism, that the exhaust from a uniflow engine may be divided into volumes at different pressures and the steam 50 conducted to different final deliveries as desired for utilization of the exhaust steam in other subsidiary apparatus such as a heating plant, or for exhaust to the atmosphere

or condenser, or both, while at the same time avoiding the use of a long cylinder 55 and piston, reducing the compression to the minimum desired while at the same time taking off the final exhaust at such point as not to affect the temperature of the live steam, and securing a high engine efficiency. 60

Fourth, to construct an engine of the uniflow type capable of effecting all the functions above indicated, in which the cylinder with its coöperating live steam and exhaust steam ports and main and auxiliary exhaust 65 valves are arranged to occupy a minimum of space, and capable of being cheaply manufactured, easily assembled, inspected or repaired, while at the same time said ports and valves are so arranged, that the lower temperature of the expanded steam passing through said exhaust ports, will not be in proximity to, and affect the high temperature of the live steam passing through the admission ports and into the cylinder. 70

Fifth, to construct an engine of the uniflow type so as to greatly reduce the size and capacity of the condenser for such type of engines, which, whenever running condensing also utilizes the exhaust steam in some 80 heating system, or whatever the exhaust steam using expedient may be. 75

Other advantages and objects of the invention will appear from the detailed description of the construction and mode of 85 operation of the invention to be presently disclosed.

My invention consists of structural characteristics and relative arrangement of elements which will be hereinafter more particularly pointed out in the appended claims. 90

In the accompanying three sheets of drawings similar reference characters indicate the same parts in the several figures in which:—

Fig. 1 is a longitudinal sectional view of the engine taken on line I—I of Fig. 2;

Fig. 2 is a transverse section on line II—II of Fig. 1;

Fig. 3 is an indicator diagram representing in full lines the pressure within the cylinder when the engine is running non-condensing and the exhaust diverting valve is cut out; 100

Fig. 4 is an indicator diagram representing the pressures within the cylinder when

the engine is running non-condensing and a portion of the exhaust steam is utilized for heating or other subsidiary purposes;

Fig. 5 is an indicator diagram representing the pressures within the cylinder when the engine is running condensing and a portion of the exhaust is diverted for use in heating or other purposes;

Figs. 6 to 13 inclusive, are diagrammatic views showing the different positions of the piston, single main exhaust valve with respect to the cylinder exhaust ports, and the exhaust diverting valve with respect to the main exhaust valve and final exhaust ports, throughout one entire cycle of operation of the engine;

Fig. 14 is a fragmentary and sectional view of the final exhaust passageways and exhaust diverting valve, when the engine is running either full condensing or non-condensing and said valve has been made inoperative.

Fig. 15 is a longitudinal sectional view of the engine partly in side elevation showing the gear for properly operating the main exhaust and exhaust diverting valve.

Referring to Figs. 1 and 2, 10 indicates a steam engine cylinder having the usual live steam admission ports 11 at the end of the cylinder controlled by admission or inlet valves 12, operated by any convenient form of valve gear, not shown. Puppet valves 12 are shown for controlling the admission of the live steam to the cylinder, but any other form of live steam distribution valves may be employed, without affecting the novel features of my invention and I contemplate using other forms of said valves, if so desired. It will also be understood that while I have shown valves 12, in connection with heads 13 and cylinder 10, provided with steam jackets to construct a steam-jacketed or heated uniflow cylinder which is completely insulated, as illustrated, any other form of heads and cylinders can be readily substituted therefor, or the valves may be within the cylinder casting without in any way modifying the construction and mode of operation of the essential features of my invention to be presently described.

Cylinder 10 is provided with the usual form of short piston 14, connected with a rod 15, cross-head 15^a, connecting rod 15^b, crank 15^c to a shaft 15^d, as shown in Fig. 15. Said piston rod 15 may be properly attached to any other form of transmission mechanism, depending on the form of suitable transmission gear necessary to effect the motion desired to be transformed from the reciprocations of the piston to the valves.

Preferably at the lower side and middle section of the cylinder 10 is provided a central or auxiliary exhaust port 16, and on each side of said central or auxiliary exhaust port and between the ends of the

cylinder is properly arranged a main or end exhaust port 17 or 18, all of said three exhaust ports 16, 17 and 18 are separated and independent of each other and lead to and communicate with a common exhaust chamber 19, and each of said exhaust ports 16, 17 and 18 instead of being one continuous opening where it enters the cylinder, is preferably formed of a series of openings by providing a plurality of bridge sections 10', as shown, in order to have a proper bearing for that lower portion of the piston over the exhaust valve and also prevent the packing rings of the piston springing out, and uneven wear of the piston avoided by the staggered relations of the bridge sections 10' and cylinder openings of the ports 16, 17 and 18. Between the cylinder ends of the three exhaust ports 16, 17 and 18, and the common exhaust chamber 19, is interposed an enlarged chamber 20, preferably circular in cross-section, as shown, in which is provided an oscillating and main exhaust controlling valve 21, having cored thereto ports 22, 23, 24 and 25, communicating with each other, and port 22 adapted to register with the central exhaust port 16, port 23 registers with exhaust port 17, port 24 with exhaust port 18, and port 25 constantly in communication with ports 22, 23 and 24 of the main exhaust controlling valve 21 and the common exhaust chamber 19. Said exhaust valve 21 is preferably of the Corliss or rotary type, but any other form of single valve may be employed whether rotary, reciprocatory or oscillatory, as shown. A stem or rod 26 is attached to the exhaust valve which may be connected to any moving part of the engine to be properly oscillated, rotated or reciprocated, as shown for example in Fig. 15, by means of the crank arm 26^a, link 26^b, rocker arm 26^c, eccentric rod 26^d, and eccentric 26^e rotated by crank shaft 15^d in order that the proper ports of the exhaust valve 21 are correctly timed with respect to the cylinder exhaust ports 16, 17 and 18 and position of piston 15.

Leading from the sides of the common exhaust chamber 19 are outlets 27 and 28 controlled, respectively, by valves 29 and 30, said outlet 27 communicating with a condenser, or any other auxiliary apparatus utilizing low pressure exhaust steam, as for example a feed water heater or steam heating plant, and the outlet 28 communicating preferably with the atmosphere for purposes to be presently described.

Communicating with the lower section of the common exhaust chamber 19, and below the valve controlled outlets 27 and 28, are two outer and a central final exhaust ports or passageways 31, 32 and 33, said central port 31 communicating preferably with a steam heating system or other low pressure

steam using accessory of the plant at which the engine is installed, and the two outer ports or passageways 32 and 33 leading to and connected with a condenser or to the atmosphere.

Supported in a seat formed in and at the lower end of the common exhaust chamber 19 is an oscillating exhaust diverting valve 34 having a single port 35 adapted to register during the oscillation of the valve 34, depending on its position, with either of the ports or passageways 31, 32 or 33, whereby said ports or passageways 31, 32 or 33 are connected with the common exhaust chamber 19, and either the condenser or atmosphere or steam heating system for purposes to be hereinafter described. Said valve 34, while shown of an oscillating type, may be of any other form, whether rotary or reciprocating, and is provided with a stem or rod 36, connected to any moving part of the engine valve gear to be properly oscillated, rotated or reciprocated, as shown for example in Fig. 15, by means of the arm 36^a, link 36^b, rocker arm 36^c, eccentric rod 36^d and eccentric 36^e rotated by crank shaft 15^a in order that its port 35 is correctly timed with respect to the ports leading to the passageways 31, 32 and 33, and the position of the ports 22, 23, 24 and 25, of the valve 21, when in communication with the exhaust ports 16, 17 and 18 and exhaust chamber 19. Said rod 36 is detachably connected with the valve gear, as shown for example in Fig. 15, by disconnecting or unhooking the link 36^b from the valve arm 36^a, a common expedient and readily understood, so that the valve 34 may be made inoperative and turned in such a position as shown in Fig. 14, to cut off communication at all times between the exhaust chamber 19 and ports or passageways 31, 32 and 33, for purposes to be hereinafter explained.

The different operations of the invention throughout all its phases of movements, showing the relations of the piston 14 with the cylinder exhaust ports 16, 17 and 18, and the main exhaust valve ports 22, 23, 24 and 25 to said ports 16, 17 and 18, and the port 35 of auxiliary valve 34, diverting the exhaust into either of passageways 31, 32 or 33, when the valves 29 and 30 are in their closed position, and the outlets 27 and 28 leading from the exhaust chamber 19 are cut off, are fully shown and will be clearly understood following the motions of the piston and path of the exhaust steam indicated by the arrows in Figs. 6 to 13.

Fig. 6 shows the piston 14 approaching the end of stroke to the left and having begun to uncover the cylinder exhaust port 18, with the exhaust valve 21 in such a position to permit the first of the expanded steam to exhaust through valve ports 24

and 25, into the common exhaust chamber 19, and thence through the port 35 of exhaust diverting valve 34, and beginning to pass into the port or passageway 31 leading to the steam heating system or other low pressure steam utilizing accessories.

In Fig. 7, the piston 14 is at the end of stroke to the left, and about to receive live steam and begin stroke to the right when cylinder exhaust port 18 is completely uncovered, and the expanded steam continues to pass out port 18, through valve ports 24 and 25 into exhaust chamber 19, and thence through ports 35 and 31 into steam heating system or whatever the steam using expedient may be.

In Fig. 8, the piston 14 has closed the cylinder exhaust port 18 and the exhaust valve 21 has assumed the position to permit the expanded steam at reduced pressure and temperature to exhaust through cylinder port 16 and valve ports 22 and 25 into the exhaust chamber 19, and the exhaust diverting valve 34 has assumed such a position, so that its port 35 is in communication with the port 33, whereby the remaining vapor or expanded steam of reduced volume, temperature and pressure is conveyed to the condenser or atmosphere as the case may be.

In Fig. 9, the piston 14 has uncovered the port 18 and about to close port 16 to the exhaust, and the exhaust valve 21 has assumed such a position to permit the expanded steam of reduced pressure to pass through the cylinder exhaust ports 16 and 17 through valve ports 22, 23 and 25 into the exhaust chamber 19 and thence through exhaust diverting valve port 35 and port 33 to the condenser or atmosphere.

In Fig. 10, the piston 14 has uncovered ports 18, 16 and about to uncover port 17 and the valve 21 has closed ports 18 and 16, and the expanded steam of the following or opposite power stroke begins passing through cylinder port 17, valve ports 23, 24 and 25 into exhaust chamber 19, and the exhaust diverting valve port 35 has assumed the position to begin opening the port 31 leading to the heating system or the like.

The remaining expanded steam or low-pressure vapor trapped between the piston and cylinder head when the former is overtraveling and closing ports 17 is properly compressed to insure smooth running of the engine.

In Figs. 11, 12 and 13, the operations above indicated are the same as described with reference to Figs. 7, 8 and 9, respectively, except that the piston 14, exhaust valve 21 and exhaust diverting valve 34 are moving in the opposite direction, and the port 17 is the main or end exhaust port instead of port 18, as shown in Fig. 7, and the 130

exhaust from port 17 passes through valve port 35 into the port 31 connecting with the heating system, and the exhaust diverting valve port 35 later communicates with the 5 port 32 instead of port 33 as shown in Figs. 8 and 9.

From the foregoing disclosure of the operation of my invention, it will be seen that the cylinder exhaust ports 16, 17 and 18 are 10 only opened one after another in uniflow rotation, and the end or outer exhaust port 17 or 18 opened at the end of the stroke and not the central exhaust port 16 performs the function of the main exhaust port through 15 which the initial or primary exhaust takes place at the end of the stroke, and the outer exhaust port 17, or 18, depending whether it is the stroke to the right or left, is an auxiliary and final exhaust port for that particular stroke, so that the main or primary exhaust port for one stroke is an auxiliary and 20 final exhaust port for the opposite stroke, whereby the remaining vapor or highly expanded steam is permitted to escape and delay the compression until the piston 14 has 25 cut off and closed the end or final exhaust port 17 or 18, each of these ports 17, 18 thus forming a combined main or primary and final or auxiliary exhaust port. It will also 30 be seen that by my invention I am able to convey the greater part of the heat units remaining in the expanded steam to a steam heating system or other subsidiary apparatus of the plant, while the remaining portion 35 and highly expanded steam is conveyed to a condenser or atmosphere as the case may be thereby reducing the back pressure to a minimum, and most efficiently operating the engine. While I have shown and described 40 the ports or passageways 32 and 33 as leading to a condenser or to the atmosphere, I do not limit myself to this arrangement as one of the primary objects of my invention is to divide the exhaust steam from a uniflow 45 engine of the type disclosed into two volumes at different pressures, in order to fully utilize the heat units remaining in the exhaust steam, and at the same time not impair the high efficiency of the uniflow engine.

When the engine is to be used, so that all 50 the exhaust steam is passed out into the atmosphere or full non-condensing, the valve 29 is opened, outlet 27 is shut off by closing down the valve 29, and the exhaust diverting valve 34 is disconnected from its valve gear 55 as heretofore explained, turned and locked in the position as shown in Fig. 14, thereby cutting off said ports 31, 32 and 33 from the exhaust chamber 19 and hence the exhaust 60 passes directly from the cylinder exhaust ports 16, 17 and 18 through valve 21, into chamber 19, through the port 28 to the atmosphere. When the uniflow engine herein described is operated non-condensing as just 65 described, the indicator diagram produced is

represented by the diagram shown by the full lines *a* and *b* in Fig. 3. The dotted line *c* in Fig. 3 represents the compression line of the original and prior uniflow engines, and the shaded area between the lines *b* and *c* of Fig. 3, graphically represents the gain 70 and increased efficiency of my form of uniflow engine, wherein the clearance spaces are reduced to a minimum and abnormal compressions eliminated, over that of prior uniflow engines in which long pistons and large clearance spaces are employed. In order to 75 avoid excessive compressions in the usual form of uniflow engines, large clearance volumes at the ends of stroke are necessitated, and the percentage of the stroke of such clearances is indicated by the vertical dotted line *h* in Fig. 3.

To operate the engine full condensing the valve 29 is opened, the outlet 28 is shut off 80 by closing down the valve 30, and the exhaust diverting valve 34 is locked in the position shown in Fig. 14, as previously described, when the exhaust steam passes directly from the cylinder exhaust ports 16, 17 and 18 through valve 21 into the chamber 19 and thence through the outlet 27 to the condenser. The indicator diagram produced 85 during this operation is represented by the full line *a* and dash and dotted line *d*, of Fig. 95 3, and produces the highest possible economy for a uniflow engine.

If the ports 32 and 33 are cut off from the condenser, and it is desired to operate the 100 engine non-condensing and utilize the exhaust steam at some back pressure in one, two or three distinct and independent auxiliary apparatus, the valves 29 and 30 are 105 shut down, thus closing outlets 27 and 28, and the exhaust diverting valve 34, during 110 its oscillatory movement, when attached to the valve gear, connects the valve port 35 with either of the ports 31, 32 or 33, and lead the exhaust steam to one, or a plurality of 115 distinct and independent sources for further use, or to the atmosphere, and the resultant indicator diagram will be as illustrated by lines *e* and *f* in Fig. 4.

During the normal operation and for 120 which the engine was designed, when the 115 exhaust steam is utilized for heating or the like and the condenser is in operation, the outlets 27 and 28 are closed by shutting the valves 29 and 30, and the exhaust diverting valve 34 is connected to the valve gear, the 125 port 35 of said diverting valve communicates with the exhaust chamber 19 and in turn with the ports or passageways 31, 32 and 33 as herein explained in connection 130 with the cycle of operation illustrated in Figs. 6 to 13, inclusive. The resultant indicator diagram during this operation of the engine is represented by the full lines *g* and *h* in Fig. 5, while the dash and dotted line *i* in Fig. 5, represents the back pressure when 130

the engine is exhausting into the atmosphere. The shaded area between the lines *h* and *i* represents the gain when the engine is running on a heating system or other steam or heat utilizing accessories and condensing simultaneously over that when it is exhausting into the atmosphere without additional supply of steam.

In all the uses to which the present invention is applied and herein disclosed, whether the exhaust is diverted to the atmosphere, heating plant, condenser, or different combinations of such diversions, if running on a short cut off, the influence of the additional clearance volume is practically negligible, for the reason, that when during the expansion of the live steam the piston 14 uncovers ports 16 and 18 as shown in Figs. 9, 10, and 13, that before this additional volume of the ports 16 and 18 is in communication with the cylinder volume, the live steam pressure and temperature of the steam have decreased to such an extent, that the detriment to the expansive powers of the live steam may be disregarded compared with the important benefits obtained as herein pointed out. If the engine is run on a long cut-off, that is thirty per cent. or more, the additional clearance volume will be filled with live steam and its hurtful influence is entirely eliminated and these additional clearance spaces do not affect the compression as the clearances employed at the ends of the cylinder are no more than that employed in any other high grade counterflow steam engine.

From the foregoing disclosure as to the construction, mode of operation and advantages of my invention, it will be readily seen that I have evolved not only a new type of uniflow engine but a most efficient arrangement and combination of elements for operating a uniflow engine, and separate or subdivide the exhaust steam from said engine, so that I am capable of supplying a heating plant or other accessory apparatus of the plant with said divided exhaust steam without extra supply of steam, and operate the same with the highest economy, and without in any way affecting the highly efficient operation of the engine under all working conditions, and while I have described and shown my preferred form of invention, I am not limited to this specific form, as many changes and modifications will readily suggest themselves to any one skilled in the art, as, for example, any well known and common form of valve mechanism for controlling the exhaust and diverting ports may be substituted for the valves shown in the drawings and within the scope of the claims without departing from the spirit of my invention.

I do not claim in this application, the disclosed construction of uniflow engine *per se*, that is the arrangement of a uniflow engine provided with three cylinder exhaust ports

as this engine is the subject-matter of a separate application filed by me April 22, 1916, and Serial No. 92,891.

What I claim is:

1. A steam engine of the uniflow type comprising a cylinder, a piston within the cylinder, a live steam inlet port at each end of the cylinder, means for controlling the admission of live steam through said live steam ports and to the opposite sides of the piston, the combination of two distinct and independent combined main and final exhaust ports at different and separated sections along the length of the cylinder, an intermediate exhaust port located between the two combined main and final exhaust ports and substantially at the center of the cylinder, a single valve controlling said three exhaust ports, three distinct and independent cylinder-exhaust-diverting ports, and a single-slot-ported exhaust-diverting-valve cooperating with the single valve controlling the three separated and independent cylinder exhaust ports and controlling the diversion of the exhaust steam of a uniflow cylinder into said three distinct and independent cylinder-exhaust-diverting-ports at different pressures, whereby the main exhaust charge expelled from the cylinder at the end of the power stroke through the distinct and independent combined main and final exhaust port when acting as main exhaust port is diverted into one of said independent cylinder-exhaust-diverting-ports and the remaining exhaust steam expelled from the cylinder at a lower pressure on the return or exhaust stroke successively through the intermediate exhaust port and through the independent main and final exhaust port when acting as final exhaust port into another of said independent cylinder-exhaust-diverting-ports.

2. A steam engine of the uniflow type comprising a cylinder, a piston within the cylinder, a live steam inlet port at each end of the cylinder, means for controlling the admission of live steam through said live steam ports and to the opposite sides of the piston, the combination of two distinct and independent combined main and final exhaust ports at different and separated sections along the length of the cylinder, an intermediate exhaust port located between the two combined main and final exhaust ports and substantially at the center of the cylinder, a single four-ported valve controlling said three exhaust ports, three distinct and independent cylinder-exhaust-diverting ports and a single-slot-ported exhaust-diverting-valve cooperating with the single four-ported valve controlling the three separated and independent cylinder exhaust ports and controlling the diversion of the exhaust steam of a uniflow cylinder into said three distinct and independent cylinder-exhaust-diverting-

- ports at different pressures, whereby the main exhaust charge expelled from the cylinder at the end of the power stroke through the distinct and independent combined main and final exhaust port when acting as main exhaust port is diverted into one of said independent cylinder-exhaust-diverting-ports and the remaining exhaust steam expelled from the cylinder at a lower pressure on the return or exhaust stroke successively through the intermediate exhaust port and through the independent main and final exhaust port when acting as final exhaust port into another of said independent cylinder-exhaust-diverting-ports.
3. A steam engine of the uniflow type comprising a cylinder, a piston within the cylinder, a live steam inlet port at each end of the cylinder, means for controlling the admission of live steam through said live steam ports and to the opposite sides of the piston, the combination of two distinct and independent combined main and final exhaust ports at different and separated sections along the length of the cylinder, an intermediate exhaust port located between the two combined main and final exhaust ports and substantially at the center of the cylinder, a single oscillating four-ported valve controlling said three exhaust ports, three distinct and independent cylinder-exhaust-diverting ports and a single-slot-ported exhaust-diverting-valve coöperating with the single four-ported valve controlling the three separated and independent cylinder exhaust ports and controlling the diversion of the exhaust steam of a uniflow cylinder into said three distinct and independent cylinder-exhaust-diverting-ports at different pressures, whereby the main exhaust charge expelled from the cylinder at the end of the power stroke through the distinct and independent combined main and final exhaust port when acting as main exhaust port is diverted into one of said independent cylinder-exhaust-diverting-ports and the remaining exhaust steam expelled from the cylinder at a lower pressure on the return or exhaust stroke successively through the intermediate exhaust port and through the independent main and final exhaust port when acting as final exhaust port into another of said independent cylinder-exhaust-diverting-ports.
4. A steam engine of the uniflow type comprising a cylinder, a piston within the cylinder, a live steam inlet port at each end of the cylinder, means for controlling the admission of live steam through said live steam ports and to the opposite sides of the piston, three distinct and independent primary exhaust ports constituting one auxiliary and two combined main and final exhaust ports at different and separated sections along the length of the cylinder and the outer ports next to the cylinder ends removed from said ends not less than the length of the piston, a single valve controlling said three primary exhaust ports, a plurality of independent secondary exhaust ports, and an exhaust diverting valve in periodical coöperation with the single valve controlling the three primary exhaust ports and for controlling the diversion of the exhaust steam of each engine stroke, diverting the initial or main charge of exhaust steam at the end of the stroke passing through the outer port next to the cylinder end into one of said independent secondary exhaust ports and the remaining exhaust steam passing through the other and independent ports into another of said independent secondary exhaust ports at a lower pressure.
5. A steam engine of the uniflow type comprising a cylinder, a piston within the cylinder, a live steam inlet port at each end of the cylinder, means for controlling the admission of live steam through said live steam ports and to the opposite sides of the piston, an auxiliary exhaust port at substantially the center section of the cylinder, a combined main and final exhaust port between the auxiliary exhaust port and each end of the cylinder, a single valve controlling the auxiliary exhaust port and the two combined main and final exhaust ports, said valve constructed, arranged and operated whereby the main exhaust port of one stroke becomes a final exhaust port during the following stroke, a plurality of independent exhaust passageways and an exhaust diverting valve arranged and constructed to divert the exhaust passing through the two main exhaust ports into one of said passageways and the exhaust passing through the auxiliary and final exhaust ports into another of said passageways.
6. A steam engine of the uniflow type comprising a cylinder, a piston within the cylinder, a live steam inlet port at each end of the cylinder, means for controlling the admission of live steam through said live steam ports and to the opposite sides of the piston, an auxiliary exhaust port at substantially the center section of the cylinder, a combined main and final exhaust port between the auxiliary exhaust port and each end of the cylinder, a single oscillating and ported valve controlling the auxiliary exhaust port and the two combined main and final exhaust ports, said valve constructed, arranged and operated whereby the main exhaust port of one stroke becomes an auxiliary end exhaust port during the following stroke, a plurality of independent exhaust passageways and an exhaust diverting valve arranged and constructed to divert the exhaust passing through the two main and final exhaust ports into one of said passageways.

ways and the exhaust passing through the auxiliary and end exhaust ports into another of said passageways.

7. A steam engine of the uniflow type comprising a cylinder, a piston within the cylinder, a live steam inlet port at each end of the cylinder, means for controlling the admission of live steam through said live steam ports and to the opposite sides of the piston, a central auxiliary exhaust port at substantially the center section of the cylinder, a combined main and auxiliary exhaust port between the central auxiliary exhaust port and each end of the cylinder, a single valve controlling the central auxiliary exhaust port and the two combined main and auxiliary exhaust ports, a plurality of independent exhaust passageways, and an exhaust diverting valve arranged and constructed to divert the exhaust passing through the combined main and auxiliary exhaust ports when acting as main exhaust ports into one of said passageways and the exhaust passing through the auxiliary exhaust ports into another of said passageways.

8. A steam engine of the uniflow type comprising a cylinder, a live steam inlet port at each end of the cylinder, means for controlling the admission of the live steam through said live steam ports and to the opposite sides of the piston, three distinct and independent exhaust-ports constituting an intermediate port and two combined main and final exhaust ports located at different and separated sections along the length of the cylinder, a uniflow-cylinder exhaust chamber, a single valve controlling the three exhaust-ports and outlet into the cylinder-exhaust chamber, a plurality of independent uniflow-cylinder exhaust-diverting-ports, and a single exhaust-diverting-valve cooperating with the single valve controlling the three exhaust-ports and controlling the diversion of the exhaust steam of a uniflow cylinder from the cylinder exhaust chamber into said plurality of independent uniflow cylinder exhaust-diverting-ports whereby the exhaust steam passing through the main-exhaust-port at the end of the stroke is diverted into one of said independent uniflow cylinder exhaust-diverting-ports and the remaining exhaust steam of lower pressure passing successively through the intermediate and final exhaust ports into another of said independent uniflow cylinder exhaust-ports.

9. A steam engine of the uniflow type comprising a cylinder, a live steam inlet port at each end of the cylinder, means for controlling the admission of the live steam through said live steam ports and to the opposite sides of the piston, three distinct and independent exhaust-ports constituting an intermediate port and two combined main

and final exhaust ports located at different and separated sections along the length of the cylinder, a uniflow-cylinder exhaust chamber, a single four-ported valve controlling the three exhaust-ports and outlet into the cylinder-exhaust chamber, a plurality of independent uniflow-cylinder exhaust-diverting-ports, and a single exhaust-diverting-valve cooperating with the single four-ported valve controlling the three exhaust-ports and controlling the diversion of the exhaust steam of a uniflow cylinder from the cylinder exhaust chamber into said plurality of independent uniflow cylinder exhaust-diverting-ports whereby the exhaust steam passing through the main-exhaust-port at the end of the stroke is diverted into one of said independent uniflow cylinder exhaust-diverting-ports and the remaining exhaust steam of lower pressure passing successively through the intermediate and final exhaust ports into another of said independent uniflow cylinder exhaust-ports.

10. A steam engine of the uniflow type comprising a cylinder, a live steam inlet port at each end of the cylinder, means for controlling the admission of the live steam through said live steam ports and to the opposite sides of the piston, three distinct and independent exhaust-ports constituting an intermediate port and two combined main and final exhaust ports located at different and separated sections along the length of the cylinder, a uniflow-cylinder exhaust chamber, a single oscillating four-ported valve controlling the three exhaust-ports and outlet into the cylinder-exhaust chamber, a plurality of independent uniflow-cylinder exhaust-diverting-ports, and a single exhaust-diverting-valve cooperating with the single four-ported valve controlling the three exhaust-ports and controlling the diversion of the exhaust steam of a uniflow cylinder from the cylinder exhaust chamber into said plurality of independent uniflow cylinder exhaust-diverting-ports whereby the exhaust steam passing through the main-exhaust-port at the end of the stroke is diverted into one of said independent uniflow cylinder exhaust-diverting-ports and the remaining exhaust steam of lower pressure passing successively through the intermediate and final exhaust ports into another of said independent uniflow cylinder exhaust-ports.

11. A steam engine cylinder having integrally-cast therein intermediate and combined main and auxiliary cylinder exhaust ports, an exhaust-valve-chamber, a common cylinder-exhaust chamber, a cylinder-exhaust-diverting-valve-chamber and separate final cylinder-exhaust-ports communicating with the exhaust chamber through an exhaust-diverting-valve, in combination with a piston within the cylinder controlling the

- inlets of said intermediate and combined main and auxiliary exhaust ports, a single valve controlling the communication between the several cylinder exhaust ports and cylinder-exhaust-chamber successively in uniflow rotation and thereby imparting alternately to the combined ports of said cylinder exhaust ports the functions of main and auxiliary exhaust ports, and a single and ported 5 valve controlling independently and mechanically operated the communication of the cylinder-exhaust-chamber with the final cylinder-exhaust-ports in synchronism with the exhaust valve and selectively connecting 10 said final cylinder-exhaust ports with said cylinder-exhaust-chamber.
12. A steam engine of the uniflow type comprising a cylinder, a piston within the cylinder, a live steam inlet port at each end 20 of the cylinder, means for controlling the admission of live steam through said live steam ports and to the opposite sides of the piston, a plurality of distinct and independent main, intermediate and final cylinder exhaust ports at different and separated sections along the length of the cylinder, an exhaust chamber communicating with the cylinder exhaust ports and having an outlet controlled by a valve, a single valve controlling the communication of the plurality 25 of independent cylinder exhaust ports with the exhaust chamber, a plurality of exhaust passageways in communication with the exhaust chamber and a single exhaust diverting valve controlling the communication of the 30 exhaust chamber with the exhaust passageways.
13. A steam engine of the uniflow type comprising a cylinder, a piston within the cylinder, a live steam inlet port at each end 35 of the cylinder, means for controlling the admission of live steam through said live steam ports and to the opposite sides of the piston, a plurality of distinct and independent intermediate and combined main and final cylinder exhaust ports at different and separated sections along the length of the cylinder, an exhaust chamber communicating 40 with said cylinder exhaust ports and having two outlets each of which is controlled by a valve, a single valve controlling the communication of the plurality of independent cylinder exhaust ports with the exhaust chamber, a plurality of exhaust passageways in communication with the exhaust chamber and a single exhaust diverting valve controlling the communication of the 45 exhaust chamber with the exhaust passageways.
14. A steam engine of the uniflow type comprising a jacketed and completely insulated and steam heated cylinder, a piston within the cylinder, a live steam inlet port at each end of the cylinder, means for controlling the admission of live steam through 50
- said live steam ports and to the opposite sides of the piston, three distinct and independent exhaust ports constituting one intermediate and two combined main and auxiliary exhaust ports at different and separated 70 sections along the length of the cylinder, a single valve controlling the three exhaust ports, a plurality of independent exhaust passageways, and an exhaust diverting valve for controlling the diversion of the exhaust steam into said plurality of independent exhaust passageways.
15. A steam engine of the uniflow type comprising a jacketed and completely insulated and steam heated cylinder, a piston 80 within the cylinder, a live steam inlet port at each end of the cylinder, means for controlling the admission of live steam through said live steam ports and to the opposite sides of the piston, three distinct and independent exhaust ports constituting one intermediate and two combined main and auxiliary exhaust ports at different and separated 85 sections along the length of the cylinder, a single four-ported valve controlling the three exhaust ports, in combination with a plurality of independent exhaust passageways, and an exhaust diverting valve for controlling the diversion of the exhaust steam into said plurality of independent exhaust passageways.
16. A steam engine of the uniflow type comprising a cylinder having a central exhaust port and a combined main and auxiliary exhaust port between said central port 100 and each end of the cylinder arranged to be covered and uncovered by the piston, in combination with valve mechanism controlling each of said ports and acting to secure the primary exhaust of the cylinder through one 105 of said combined main and auxiliary exhaust ports when the piston has passed said port and to open the central port and other combined main and auxiliary exhaust port on the return stroke of the piston for further 110 exhaust, and means for delivering said exhaust steam in separate volumes at different pressures.
17. A steam engine of the uniflow type comprising a cylinder having a central exhaust port and a combined main and auxiliary exhaust port between said central port 115 and each end of the cylinder arranged to be covered and uncovered by the piston, in combination with valve mechanism controlling each of said ports and acting to secure the primary exhaust of the cylinder through one 120 of said combined main and auxiliary exhaust ports when the piston has passed said port and further exhaust through the central port on the return stroke until the piston has passed said central port, and to open the other combined main and auxiliary port for final exhaust through said port on the return stroke of the piston until the piston has 125 130

passed said port, and means for delivering said final exhaust separately from the primary and central exhausts.

18. A steam engine of the uniflow type comprising a cylinder having a central exhaust port and a combined main and auxiliary exhaust port between said central port and each end of the cylinder arranged to be covered and uncovered by the piston, in combination with valve mechanism controlling each of said ports and acting to secure the primary exhaust of the cylinder through one of said combined main and auxiliary exhaust

ports when the piston has passed said port and to open the central port and other combined main and auxiliary exhaust port on the return stroke of the piston for further exhaust, a single passage receiving said primary and further exhausts, and diverting valve mechanism for delivering said exhaust steam from said passage in separate volumes at different pressures. 15

In testimony whereof I hereby affix my signature.

FREDERICK W. BÖSCH.
